(57) **CLAIM**

We claim the ornamental design for a scanner for tomographic imaging apparatus, as shown and described.

DESCRIPTION

FIG. 1 is a front view of a scanner for tomographic imaging apparatus showing our new design;

FIG. 2 is a left view of the scanner design shown in FIG. 1; FIG. 3 is a front perspective view of the scanner design shown in FIG. 1;

FIG. 4 is a rear perspective view of the scanner design shown in FIG. 1;

FIG. 5 is a top view of the scanner design shown in FIG. 1; FIG. 6 is a rear view of the scanner design shown in FIG. 1; FIG. 7 is a front perspective view of the scanner design shown in FIG. 1; and

FIG. 8 is a right view of the scanner design shown in FIG. 1; and,

FIG. 9 is a bottom view of the scanner design shown in FIG. 1.

The broken lines in the drawing views represent environmental subject matter and form no part of the claimed design.
